Specification for Design.

Patented Mar. 8, 1921.

Application filed September 26, 1919. Serial No. 326,690. Term of patent 7 years.

To all whom it may concern:

Be it known that I, THORNTON G. GRAHAM, a citizen of the United States, residing at Chicago, in the county of Cook and State of Illinois, have invented a new, original, and ornamental Design for Tire-Casings, of which the following is a specification, reference being had to the accompanying drawing forming a part thereof.

Figure 1 is a fragmental plan view of a

tire casing, showing my new design. Fig. 2 is a vertical sectional view taken on line 2—2 of Fig. 1.

I claim:

The ornamental design for a tire casing substantially as shown.
